UNITED STATES PATENT OFFICE

HARRY READ, OF YORK, PENNSYLVANIA, ASSIGNEE TO READ MACHINERY COMPANY,
OF YORK, PENNSYLVANIA, A CORPORATION OF PENNSYLVANIA

MIXING MACHINE

Application filed September 13, 1929. Serial No. 392,452.

This invention relates to mixing machines and an important object of the invention is the production of a device of this character particularly adapted for construction in the larger sizes, which is of such construction that the mixing bowl may be very readily manipulated in the installation or removal thereof and may be very readily adjusted so that the agitator employed with the mixing bowl 10 may be disposed at various depths in the batch contained in the mixing bowl.

A further object of the invention is the production of an apparatus for adjusting the bowl, when in position on the machine, of 15 such character that the bowl may be very rapidly shifted from one to another of its positions and may be securely held in any of its positions.

A further object of the invention is the 20 production in an apparatus of the character just described of a handle controlling the shifting of the bowl which serves likewise as a lock for maintaining the bowl in its adjusted positions.

A still further object of the invention is 25 to provide a novel and improved transmission for use with an apparatus of this character and a control for this transmission enabling the use of a fairly complicated type of transmission having a great number of speed changes and which at the same time is of such simple character that it might be manipulated by employees having only a slight mechanical knowledge.

These and other objects I attain by the 30 construction shown in the accompanying drawings wherein for the purpose of illustration I have shown a preferred embodiment of my invention, and wherein:

Fig. 1 is a side elevation of a mixing machine constructed in accordance with my invention;

Fig. 2 is an end elevation of the apparatus shown in Fig. 1;

Fig. 3 is a fragmentary detail view showing the manner of connecting the actuating shaft and the paddle;

Fig. 4 is a section on line 4—4 of Fig. 3;

Fig. 5 is a detail sectional view on line

5—5 of Fig. 3 showing the latching yoke in its latching position in solid lines and in its released position in dotted lines;

Fig. 6 is a plan view of the apparatus with the cover plate removed to reveal the transmission mechanism;

Fig. 7 is a section on line 7—7 of Fig. 6 and

Fig. 8 is a section on line 8—8 of Fig. 7.

Referring now more particularly to the drawings, the numeral 10 designates a suitable base from which rises a standard 11 the upper end of which is in the form of a transversely extending hollow head 12 constituting, as hereinafter more fully explained, a gear casing one end of which overhangs the base. At the corresponding side of standard 11 a pair of vertically-extending stationary shafts 13 are mounted, these shafts 15 slidably supporting a yoke 14 having outwardly-extending arcuate arms 15 adapted to receive therebetween the mixing bowl 16.

Mixing bowl 16 is open-topped and is provided upon its exterior adjacent the top thereof with an outstanding flange 17 which is adapted to rest upon the extremities of the arms and is provided with apertures for the reception of projecting pins 18 projecting upwardly from such extremities. Yoke 14 is formed at its upper end with a lug 19 notched as indicated at 20 for the reception of the inner edge of this flange and the bowl is thus held both against vertical displacement and against circumferential movement.

Yoke 14 at its inner face is formed as a vertical rack 21. Upon the horizontal pivot shaft 22 extending through the standard 11 I secure a segment gear 23 meshing with this rack. One end of shaft 22 projects through the side wall of standard 11 and is there equipped with a latch lever 24, the latch 25 of which co-acts with a segmental rack 26 to maintain the lever and thereby the segmental gear 23 and rack 21 in any desired vertically adjusted position. These vertically adjusted positions will correspond to vertically adjusted positions of the bowl and thus means are provided for determining exactly the depth of engagement of the mixing

paddle in the bowl and, accordingly, to extend the agitation of the mixture.

Above the shaft 22 and adjacent the top of the standard 11 I provide a second horizontal transversely-extending shaft 27 which is rotatably mounted in the walls of the standard and which has mounted thereon an organization including a central relatively small pulley element 28 and larger pulley elements 29 arranged at opposite sides thereof and fixed against rotation with relation thereto. The yoke, and more particularly the upper end of the yoke, has secured thereto an attaching eye 30 over which extends a cable 31 which is secured to pulley 28. Each of pulleys 29 has secured thereto a cable 32, the lower end of which is attached to a counter-weight W. These counter-weights are thus disposed at opposite sides of the segment gear 23 so that in their raising and lowering operations they will not interfere with the movements thereof.

The transmission housing 12 hereinbefore referred to is divided by partitions 34 and 35 into main and secondary transmission chambers 36 and 37 and an output drive chamber 37—*a*. In the partitions 34 and 35 I journal shafts 38 and 39, shaft 38 having secured thereto within the chamber 36 a plurality of fixed gears indicated at 40, 41 and 42 while shaft 39 has splined thereto a triple gear 43 having elements for co-action with each of gears 40, 41 and 42. Within the compartment 37 I dispose shafts 44 and 45, shaft 44 axially aligning with shaft 38 and having bearing in a clutch gear 46 which is carried by the end of shaft 38 and disposed in compartment 37. Shaft 45 if desired may be axially aligned with shaft 39 for convenience in effecting the mounting thereof, which will be obvious from the drawings.

which will be obvious from the drawings.

Shaft 45 has secured thereto a pinion 47 meshing with clutch gear 46 and has rotatably mounted thereon a clutch gear 48 which 45 meshes with a pinion 49 secured to shaft 44. The co-acting clutch elements of these clutch gears 46 and 48 are secured to their associated shafts and the clutches 50 connecting the respective elements are preferably of 50 the expanding type embodying expansion bands 51 between the ends of which a tapered clutch finger 52 may enter to provide the necessary expansion. Clutch fingers 52 are rotatably mounted upon their respective shafts and are connected for simultaneous movement by a shifting yoke 53.

60 Rotatably mounted in the end walls of casting 12 and in the partitions 34 and 35 and projecting through the front wall of the housing 12 is a control shaft 54 the upper end of which is provided with a spoke wheel 55. The outboard bearing 56 at the front end wall of the transmission housing 12 is formed in its upper surface with a longitudinally 65 extending slot 57, this slot inter-

rupting at spaced intervals circumferentially extending slots 58, 59 and 60. Within the compartment 37 this shaft has splined thereto a worm 61 upon which is mounted a nut 62 bearing yoke 53. Rotatably mounted upon the shaft 54 within compartment 36 is a shifting yoke 63 for triple gear 43, this yoke being held against longitudinal movement by collars 64. 70

By shifting shaft 54 longitudinally, to 75 align pin 65 thereof with one or the other of circumferential slots 58, 59 and 60 of bearing 56, triple gear 43 may be caused to bring its proper gear element in engagement with either of the gears 40, 41 or 42. Longitudinal movement of the shaft can, of course, only be accomplished when pin 65 is aligned with the longitudinally extending slot 57 and at this time nut 62 and yoke 53, and accordingly clutch fingers 52 will be 80 disposed in an intermediate or neutral position. Shaft 44 is driven and since its sole connection with the input shaft 38 of the main transmission is either directly through clutch gear 46 or through clutch gear 46 by 85 way of clutch gear 48 it follows that the gearing is actually in a neutral position at any time when the triple gear 43 is being shifted. When the selection has been made, either of gears 46 or 48 may be clutched to 90 its respective shaft by rotating shaft 54 clockwise or counterclockwise thus causing rotation of worm 61 and a corresponding movement of yoke 53 and of the clutch finger. When clutch gear 46 is clutched to its 95 shaft 44 the drive is directly from this shaft to shaft 38 and from shaft 38 to shaft 39 through the selected gear 40, 41 or 42 and its associated element of the triple gear. When clutch gear 48 is clutched to its shaft 100 45 the drive is from shaft 44 through pinion 49, clutch gear 48, shaft 45, pinion 47 and gear 46. Through the pinions 47 and 49 a substantial reduction in speed of operation is obtained so that for each gear ratio 105 provided in the main transmission compartment two speeds are available.

Shaft 39 forms the output shaft of the main transmission and projects into the mixer drive chamber 37a. In this drive chamber there is disposed a vertically extending shaft 66 having secured thereto a bevel gear 67 engaged by a bevel pinion 68 carried by the shaft 39. This shaft projects through the lower end of the transmission housing axially to the bowl 16 and through an orbit gear 69 secured to the lower face of this housing. Secured to the lower end of the shaft is a disc 70 the periphery of which is provided with an upstanding flange 71 forming an oil guard and surrounding the orbit gear 69. This disc has an eccentrically disposed downwardly projecting bearing chamber 72 in the upper and lower ends of which are disposed bearing 125 130 135 140 145 150 155 160 165 170 175 180 185 190 195 198 200 205 210 215 220 225 230 235 240 245 250 255 260 265 270 275 280 285 290 295 300 305 310 315 320 325 330 335 340 345 350 355 360 365 370 375 380 385 390 395 400

ings 73 for the reception of a vertically extending shaft 74 the upper end of which has a planet pinion 75 meshing with the orbit gear 69.

The lower end of shaft 74 has secured thereto a collar 76 preferably provided with an oil retaining flange 77 engaging the lower end of bearing chamber 72. The lower face of this collar is provided with a downwardly projecting lug and the shaft below the collar is adapted to project into a sleeve-like extension 78 formed upon the upper end of mixing paddle 33. The upper end of this sleeve is conical with the base end thereof upwardly disposed and is notched as at 79 for the reception of the lug 80 of the collar.

Pivoted to the collar 76 is a U-shaped clamping yoke 81 formed of spring metal. The pivotal connections of this yoke with the collar preferably comprise inturned terminal portions 82 upon the arms thereof extending into sockets 83 formed in the collar. The collar adjacent the free ends of the arms of the yoke has formed thereon wedge-shaped lugs 84 which extend at right angles to the yoke when in its clamping position and have the smaller ends thereof engaged with this yoke. The yoke, when in its clamping position, is engaged with the sleeve-like extension 78 of the mixing paddle 33 at its junction with the conical upper end 85 thereof. Since this yoke to move from this position must overcome the resistance caused by expansion of the arms through their engagement with the wedges 84, it follows that the yoke will normally maintain this position and so serve to hold the sleeve-like extension and the paddle from downward movement even when the shaft 74 is rotating fairly rapidly and there is a considerable centrifugal force exerted against the bight of the yoke.

The mixing paddle 33 is preferably substantially spade-shaped as illustrated and the bottom of the mixing bowl at its center is provided with a conical projection so that there are no dead spots in the mixing bowl which will not be reached by the paddle.

In operation of the device the bowl is placed in position upon the yoke and adjusted to the proper height, the stirring paddle is then started in operation by selecting the proper gear and engaging the proper clutch. This will cause rotation of shaft 66 thus rotating disc 70 which carries with it the shaft 74. Rotation of disc 70 thus serves to accomplish rotation of shaft 74 through the engagement of gear 75 with the orbit gear 69. The wide variation in available speeds enables mixtures to be produced which cannot be produced with the ordinary mixing machine and enables the contents of the bowl to be agitated at precisely the desired speed. Manipulation of the bowl in application thereof and in the adjustment thereof to its various positions is greatly facilitated and

the operation of the machine thus rendered much more efficient.

Since the construction hereinbefore illustrated is capable of a considerable range of change and modification without in any manner departing from the spirit of my invention, I do not wish to be understood as limiting myself to such specific construction except as hereinafter claimed.

I claim:

1. In combination, a change speed transmission including clutch gearing for effecting speed changes therein, a reversely shiftable clutch-operating element for alternately actuating said clutches, a second transmission receiving the output of the first-named transmission and embodying a shiftable speed changing gear element, a shaft rotatably and longitudinally shiftably directed through said transmissions, connections between said shaft and the clutch-operating element whereby when the shaft is rotated the clutch-operating element is shifted in a direction depending upon the direction of rotation of the shaft and a connection between the shiftable gear element of the second transmission and said shaft permitting independent rotation of the shaft while operatively shifting said gear upon longitudinal shifting movements of the shaft.

2. In combination, a change speed transmission including clutch gearing for effecting speed changes therein, a reversely shiftable clutch-operating element for alternately actuating said clutches, a second transmission receiving the output of the first-named transmission and embodying a shiftable speed changing gear element, a shaft rotatably and longitudinally shiftably directed through said transmissions, connections between said shaft and the clutch-operating element whereby when the shaft is rotated the clutch-operating element is shifted in a direction depending upon the direction of rotation of the shaft, a connection between the shiftable gear element of the second transmission and said shaft permitting independent rotation of the shaft while operatively shifting said gear upon longitudinal shifting movements of the shaft, and means preventing longitudinal shifting of the shaft until the shaft has been rotated to a position placing said clutch-operating member in an intermediate neutral position.

3. In combination, a change speed transmission including clutch gearing for effecting speed changes therein, a reversely shiftable clutch-operating element for alternately actuating said clutches, a second transmission receiving the output of the first-named transmission and embodying a shiftable speed changing gear element, a shaft rotatably and longitudinally shiftably directed through said transmissions, connections between said shaft and the clutch-operating element

whereby when the shaft is rotated the clutch-operating element is shifted in a direction depending upon the direction of rotation of the shaft, a connection between the shiftable gear element of the second transmission and said shaft permitting independent rotation of the shaft while operatively shifting said gear upon longitudinal shifting movements of the shaft, and means preventing longitudinal shifting of the shaft until the shaft has been rotated to a position placing said clutch-operating member in an intermediate neutral position, comprising a bearing for the shaft having a splined slot, a pin upon the shaft operating in the slot and coves opening from opposite sides of the slot for the reception of said pin to permit rotation of the shaft effecting operation of the clutch-operating element.
